Primary Examiner — David G Muller*(74) Attorney, Agent, or Firm* — Fitch, Even, Tabin & Flannery LLP(57) **CLAIM**

The ornamental design for an enteral feeding valve, as shown and described.

DESCRIPTION

FIG. 1 is a front perspective view of an enteral feeding valve showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken line showing of parts of the drawings is included for the purpose of illustrating use and environment and forms no part of the claimed design.

1 Claim, 8 Drawing Sheets(56)
